UNITED STATES PATENT OFFICE.

WILLIAM HEYSER, OF BALTIMORE, MARYLAND.

DESIGN FOR A WINDOW TOP SASH LIFT.

SPECIFICATION forming part of Design No. 16,652, dated April 20, 1886.

Application filed March 16, 1886. Serial No. 195,475. Term of patent 7 years.

To all whom it may concern:

Be it known that I, WILLIAM HEYSER, of the city and county of Baltimore, and State of Maryland, have invented a new and original 5 Design for a Window Top Sash Lift, of which the following is a full, clear, and exact description.

Reference is to be had to the accompanying drawing, forming a part of this specification, 10 in which the drawing represents a view in perspective of a window top sash lift embodying my design, substantially as hereinafter described, and shown in the drawing.

A is the base of the lift, which, as viewed 15 from its face, presents an oblong figure. From the center of the face of its base the lift presents reverse concave upper and lower outlines or surfaces, b b, standing out in front of the base, and a further concave outline or surface 20 c, from the front margin of the base in a plane at right angles to the plane of the outlines b b. These concave outlines or surfaces b b and c terminate, respectively, at their outer ends in a protuberance, d, of circular outline

in transverse section, having its longitudinal 25 axis parallel with the face of the base transversely to the width thereof, the curved outlines or surfaces b b vanishing in the circular form of said protuberance d, and the curved outline or surface c meeting the latter at its 30 front or forward end, as shown.

Having thus described my invention, what I claim as new, and desire to secure by Letters Patent, is—

The design for a window top sash lift here- 35 in shown and described, the same consisting of an oblong base, A, with a front projection from its face presenting concave outlines or surfaces b b c, lying in different planes, and terminating in a protuberance, d, of circular 40 form in transverse section, with its longitudinal axis parallel with the face of the base transversely to the width thereof.

WILLIAM HEYSER.
